UNITED STATES PATENT OFFICE.

FERDINAND W. ADAMS, OF SAGINAW, MICHIGAN.

DETACHABLE SHOE UPPER OR OVERGAITER.

1,248,239.

Specification of Letters Patent. Patented Nov. 27, 1917.

Application filed March 29, 1917. Serial No. 153,253.

To all whom it may concern:

Be it known that I, FERDINAND W. ADAMS, a citizen of the United States, residing at the city of Saginaw, in the county of Saginaw and State of Michigan, have invented certain new and useful Improvements in Detachable Shoe Uppers or Overgaiters; and I do declare the following to be a full, clear, and exact description of the invention, such as will enable others skilled in the art to which it appertains to make and use the same.

This invention relates generally to apparel, more particularly to certain new and useful improvements in detachable shoe uppers or over-gaiters.

One object of the invention is to provide a detachable fancy cloth or other upper or over-gaiter for shoes which can be readily attached to or removed from a shoe, and which is provided with means for preventing wrinkling in order that it will present a neat appearance to the casual observer.

Another object of the invention is to provide a detachable upper or over-gaiter for shoes which is split at its front instead of at the side, as is true regarding devices now on the market, and which is provided with eyelets or hooks for receiving a lacing, thereby presenting the appearance of an ordinary non-detachable shoe upper.

A further object of the invention is to provide an improved means for securing the shoe upper or over-gaiter in position upon the shoe.

A still further object of the invention is to generally improve upon devices of this character by the provision of an extremely simple, strong, durable and inexpensive construction, and one which will be efficient and reliable and well adapted to the purpose for which it is designed.

With these and numerous other objects in view the invention consists of certain details of construction, and the combination and arrangement of parts as will be herein-after fully described and claimed.

In the accompanying drawings forming a part of the application, and in which similar reference characters designate like parts throughout the several views:—

Figure 1 is a side elevation of a shoe having a detachable upper, constructed in accordance with this invention, attached thereto, one corner of the upper edge of the upper being turned back and being partly in sec-

tion to show the interior construction of the same;

Fig. 2 is a front view of the lower portion of the upper;

Fig. 3 is a bottom plan view of the shoe with the upper attached, showing the positions of the two straps; and

Fig. 4 is a perspective view of the adjacent ends of the forwardmost lower straps about to be hooked together.

Referring more particularly to the drawings, the numeral 1 designates a shoe, which may be either a low shoe or a high top shoe, and 2 the detachable upper or over-gaiter forming the subject matter of the present invention. This upper or over-gaiter 2 may be of cloth or other suitable material and of a color distinguishable from that of the shoe, and ornamented in any manner desired.

Unlike the detachable shoe uppers or over-gaiters now on the market, commonly called "spats," this upper is split at its front and provided with suitable fastening elements, here shown in the form of eyelets 3 for receiving a lacing. However, it is to be understood that any other type of fastening elements may be employed. Secured to the interior sides of the upper 2 at its front edges and extending from the top to the bottom thereof, are resilient stays 4. These may be placed either inwardly of the line or series of eyelets 3 or outwardly of said eyelets, as is most desirable.

Secured to the interior sides of the upper 2 in any suitable manner and arranged at the bottom edges of the same are additional stays, preferably composed of sections 5 and 6, the sections 5 having their forward ends rigidly secured at 7 to the lower ends of the front stays 4 and being provided with co-operating fastening elements 8 and 9. These sections 5 are adapted to pass over the upper portion or waist band of the foot when applied to use. The sections 6 are arranged at the extreme lowermost portions of the upper and are disposed adjacent the instep.

A pair of straps 10 and 11 are secured to the opposite sides of the upper 2 and are adapted to pass beneath the instep when said upper is applied to a shoe. The strap 10 is to be disposed adjacent the forward portion or breast of the heel of the shoe and prevents the upper from working forward, while the strap 11 is disposed adjacent the extreme forward end of the instep to draw

the waist band tight around the shoe. These straps are provided with suitable take-up means, here shown in the form of buckles 12 somewhat similar to the ordinary suspender buckles.

When the device is applied to use, the fastening elements 8 and 9 are first engaged and the straps 10 and 11 are then inserted through the buckles and tightened. The 10 upper is then laced the same as an ordinary shoe, and after this is done it will be found that the stays 4 prevent wrinkling of the extreme upper portion of the upper and force the lower portion downwardly toward the 15 toe of the shoe. The stays 5 prevent the upper from working upwardly and hold it tight around the shoe or foot. The upper will thus fit snugly and properly around the shoe and foot and will present a very 20 neat appearance. Owing to the fact that it is laced at the front instead of being buttoned or otherwise secured at the side, it will give the appearance of an ordinary 25 non-detachable upper for shoes instead of a detachable upper or over-gaiter.

From the foregoing description, taken in connection with the accompanying drawings, the construction and use of the invention will be readily understood without a 30 more extended explanation. As various changes in form, proportion, and in the minor details of construction may be resorted to without departing from the spirit of the invention, it is to be understood that I 35 do not wish to be limited to the precise construction herein shown and described.

I claim:—

1. A detachable shoe upper or over-gaiter which is split at its front and provided with fastening elements, resilient stays secured to the upper or over-gaiter at its front edges and extending from the top to the bottom thereof, and additional resilient stays secured to the upper or over-gaiter at the bottom edges thereof.

2. A detachable shoe upper or over-gaiter

which is split at its front and provided with fastening elements, resilient stays secured to the upper or over-gaiter at its front edges and extending from the top to the bottom thereof, and additional resilient stays secured to the upper or over-gaiter at the bottom edges thereof, the forward ends of the bottom stays being rigidly secured to the lower ends of the front stays.

3. A detachable shoe upper or over-gaiter which is split at its front and provided with fastening elements, resilient stays secured to the upper or over-gaiter at its front edges and extending from the top to the bottom thereof, and additional resilient stays secured to the upper or over-gaiter at the bottom edges thereof, the forward ends of the bottom stays being rigidly secured to the lower ends of the front stays and being provided with coöoperating fastening elements for connecting them together.

4. A detachable shoe upper or over-gaiter which is split at its front and provided with fastening elements, resilient stays secured to the upper or over-gaiter at its front edges and extending from the top to the bottom thereof, additional resilient stays secured to the upper or over-gaiter at the bottom edges thereof, said additional stays being made in separate sections, the forward ends of the forwardmost sections being rigidly secured to the lower ends of the front stays and adapted to be disposed on the upper part of the foot, and other sections being disposed adjacent the instep of the latter, and a strap secured to the bottom edges of the upper or over-gaiter and adapted to pass beneath the instep.

In testimony whereof I have hereunto set my hand in the presence of two subscribing witnesses.

FERDINAND W. ADAMS.
